FLUSH TANK ACTUATING MEANS

Eugene C. Petrie, Elmhurst, Ill., assignor to Crane Co., Chicago, Ill., a corporation of Illinois

Application October 31, 1956, Serial No. 619,540

1 Claim. (Cl. 4—56)

This invention relates to flush tanks or the like, particularly as used with water closets.

A principal object of the invention is to provide a new means of flush tank actuation in the matter of initiating discharge from the tank. This means of actuation incorporates the use of float means to raise the outlet valve into an open position, said float means being so caused to raise the closure member by the introduction of an additional supply of water, at the time of flushing and preferably by the use of additional valve means of a metering self-closing type, to raise the water level above that normally producing a closed ballcock to a predetermined new height sufficient to cause such actuation.

Another object is to provide flushing means in which all mechanical linkage is eliminated, the same operating hydraulically. This permits dispensing with the conventional operating lever and handle and permits the substitution of a more conveniently actuatable push button arrangement for operation of an auxiliary valve. This is important as it is adapted to a new trend which is developing towards redesigning and placing the flush tank within or behind the wall of a bathroom or the like for a more modern appearance. In this case only the push button operating means will be visible within (where recessed) or beyond the face of the wall of the room. It is not considered modern or attractive or even of good mechanical design, however, to merely mount the conventional operating handle of rather sizable proportions and related parts on the wall or access panel as it presently is on the flush tank, but rather the use of a small push button which is preferably flush with the surface of the wall or recessed therein is contemplated. The present invention would therefore fit into this new trend.

A further object is to provide for hydraulic actuation of the tank outlet valve which will permit remote operation of the flush tank. This is important inasmuch as an alternative to placing the flush tank within the wall directly behind the water closet, the same may be placed in a more remote location as behind the wall either directly or in a more removed location as in a utility room or, the same may be placed in any suitable space, preferably in an elevated position such as in a closet, false or real cabinet or otherwise waste space as in a soffit. The tank also need not be restricted to the same floor the water closet is on, but the same may be placed in the floor above in a suitable location or in storage or attic space, if sufficiently warm so as to guard against freezing. In such remote location of the tank an additional length of pipe (possibly flexible plastic) of course would be necessary between the tank outlet and water closet as well as between the auxiliary or preferably push button valve and the tank into which it discharges. It is thus seen that great flexibility is present by virtue of the present invention. In this connection, of course, the flushing control such as a push button may be mounted in the floor for foot operation.

Other objects and advantages will become more readily

2

apparent upon proceeding with the description read in light of the accompanying drawing in which.

Fig. 1 is an assembly view of a flush tank employing the preferred form of the present invention, certain parts being broken away and shown in section;

Fig. 2 is a sectional view taken along the lines 2—2 of Fig. 1; and

Fig. 3 is a view similar to Fig. 2 showing a more basic form of the invention.

Referring to the drawing in greater detail and particularly Figs. 1 and 2 thereof, the numeral 1 designates a flush tank as used for water closets or the like, said tank including the usual inlet supply line 2 at the upper end of which is secured a conventional supply valve or ballcock 3 including a float 4 which is effective to close the supply valve upon the attainment of the normal full tank water level approximately as shown at 6. It should of course be understood that this water level is subject to variation depending upon the inlet water pressure and the extend to which the float rod arm 7 may be bent in order to procure the quantity of water desired for the flushing action according to conventional practice. The supply line 2 of course passes through the bottom of the tank in fluid sealed relation at 9.

The flush tank, which may be constructed of inexpensive sheet metal or plastic for within wall or remote use as pointed out in the preamble to the specification, also includes outlet facilities such as the fitting member 13 having an outlet port therethrough and surrounded by a valve seat 14 at the top. Preferably, a flapper type closure member 16 such as that disclosed in Patent No. 2,756,437 is employed, said member being secured or mounted in the manner disclosed therein. Briefly, the closure member includes a flat seating disc-like forward portion 17 for spanning the top of the outlet opening in the closed valve position as shown and the rearwardly extending portion 18 having a transversely extending slot 19 for buttoning on or stretching over an enlarged buttonhead formation 20 surmounting the post portion 21 extending rearwardly from the outlet fitting. The closure also includes a depending buoyant portion 23 for maintaining the said closure member in a state of floatation when raised from the seat surface a sufficient amount during the flushing action until the tank water has drained out to a predetermined lower level.

According to the preferred form of the present invention, the same provides novel means for actuating the closure member so as to lift the same into a condition of self-buoyancy by virtue of its own float portion. According to this invention this lifting or actuation of the closure from its lower closed position is accomplished by the use of adequate float means such as the float member 25 positioned above the closure member. This float member is suitably attached to the closure member as by means of a downwardly extending wire or rod 26 and a flexible cord or bead chain 27 attached to the rod and closure by wire clip elements 28 and 29 respectively, the rod 26 terminating in eye or loop 30 at the lower end for attachment of the upper wire element 28. Fig. 3 shows the basic idea with the addition of a guide member or supporting arm 31 with an opening or bore 32 for passage of the wire or rod 26 therethrough. Such guiding or positioning is for the purpose of preventing the float member 25 from becoming entangled with the float rod arm 7 of the ballcock during the flushing action. As far as the basic invention is concerned the guide may be eliminated.

The basic principle of operation of this flush tank is to introduce an additional quantity of water into the tank, at the time the flushing action is desired, over the amount already present in the tank by virtue of the sup-

ply valve 3 and which normally in a properly operating tank produces a closed ballcock. Upon the introduction of such additional quantity of water, as by means of auxiliary valve 33, sufficient to raise the water to a predetermined higher level, the float member 25 will tend also to rise with the water level. Inasmuch as there is practically no slack or looseness in the connection between the float 25 and closure member in the closed valve position, the float 25 will not actually rise with the water level as additional water is being introduced but rather will become in the course of a certain time substantially submerged, thus to build up a large amount of buoyant energy. This energy will become sufficient prior to or at least substantially at the predetermined higher level to overcome the weight of the water on the closure member 16 and to raise the same from the outlet fitting 13 into the open position shown in the dotted lines in Fig. 1, so that the closure may assume a condition of self-buoyancy and move into yet a higher position. The upper position of the float member 25 corresponding to the raised position of the closure member is indicated in the dotted lines at 35 in Fig. 1. A similar higher position of the float will also be present in the Fig. 3 construction. In the latter construction the additional water must be sufficient to raise the water level in the entire tank to the predetermined higher level necessary to actuate the float member 25 in order to raise the closure 16. This would take a considerable amount of water which is not particularly desirable.

In the Figs. 1 and 2 form, therefore, an inner tank or float chamber 37 is employed having imperforate cylindrical side walls 38 and a bottom portion 39 also imperforate except for a central opening 40 for the passage of the rod 26 and for drainage of the tank member 37 there-around when the water in the flush tank has discharged during the flushing action. This inner tank is also open at the top for a purpose to be brought out hereinafter.

In this arrangement the auxiliary or additional supply valve means 33 is adapted to discharge within the inner tank 37 by means of tubing or a pipe line such as 42. In this way the quantity of water necessary to raise the water level around the float member 25 to the predetermined height necessary to cause raising of the same and of the attached closure member 16 is very drastically reduced. In fact only a small amount of water is necessary in order to cause such actuation, thus to increase the efficiency of the present invention and eliminate the wastage of water. The tank member 37 is of course suitably attached to the flush tank as by means of supports 44 (see Fig. 2) shown. Besides the member 37 serving as an inner tank for the purpose above described, it also serves as a guide or enclosing means for the float member 25 to prevent the same from floating loosely within the tank and perhaps becoming entangled with a float rod arm 7 of the ballcock.

In connection with the auxiliary or additional supply valve 33, this is preferably a push button actuated, self-closing, metering type of valve such as may be procured on the market, the internal construction of which is not believed pertinent or necessary to go into inasmuch as it does not form part of the invention. This auxiliary valve as noted in the drawing is connected by means of the piping 46 to the same source of supply as the supply pipe 2 of the flush tank is connected. The piping 46 may of course be wholly within the flush tank or outside of it as shown. Although the auxiliary valve 33 is shown mounted on the flush tank and extending through the wall 47 such as that of a bathroom or the like, the valve does not necessarily have to be so mounted on the tank. This auxiliary valve, as pointed out in the preamble to the specification, may be located at a point remote from the flush tank or, putting it in another way, the flush tank may be at a location remote from the actuating valve 33. In the latter case the piping 46 will be of additional length

as well as the piping or conduit (not shown) between the outlet fitting 13 and the water closet. It was also pointed out in the preamble that the present invention is intended to be employed in a newly designed flush tank to be positioned within or behind the wall. The present tank therefore is preferably constructed of low cost sheet metal or plastic and is designed to be placed between studding where this mounting is to be effected.

Although the self-closing, metering type of valve 33 is illustrated, it should of course be understood that other means of introducing water to the tank may be employed, if desired, which may not be automatically self-closing. If the non self-closing type of valve is used, the flush tank outlet valve would simply be actuated upon attainment of the predetermined higher water level, at which time the additional valve means or whatever means are employed could be shut off or released in the case of push button actuation.

It should be noted that no overflow tube or channel has been disclosed in the drawing. This is to illustrate that the same is not necessary for overflow purposes inasmuch as the present construction also serves as an overflow means. This action takes place as a result of rising of the float element 25 sufficiently to lift the closure or at least a portion thereof at least slightly off its seat during rising of the tank water level beyond the normal ballcock shut-off point because of a leaky ballcock for instance, thus to relieve the rising level by flow into the outlet port. The greater the rate of water rise, the greater will be the lifting of the closure member and the discharge flow. The rising water will of course enter the inner tank 37 through the opening 40 in the bottom. Should the rise be too rapid, however, as for instance where there is a relatively high inlet pressure, it is contemplated that the inner tank will rapidly fill upon the overflow stage reaching the open top of the same and overflowing thereinto, after which actuation of the closure member will take place for relief of the tank. The inner tank should therefore have its open top or at least an open portion disposed sufficiently below the top of the flush tank or any other point of leakage to safeguard the same and insure actuation of the closure member.

For refill or resealing purposes as employed with water-closets a construction such as shown in copending application Serial No. 652,281, filed April 11, 1957 may be provided.

Although certain forms have been illustrated or suggested, it is not desired to limit this invention to those forms or suggestions and other variations and changes may be made within the broad spirit of the invention. The appended claim should accordingly be liberally construed in the light of the overall inventive spirit herein involved.

I claim:

55 In a flush tank or the like including a float controlled supply valve and an outlet valve adapted to be raised from the closed valve position, float means floating in the tank water when at the normal water level producing a closed supply valve, said float means being connected to said outlet valve and effective to raise the latter upon raising of the float means to a predetermined level above the normal water level in the tank producing a closed supply valve, and means effective to supply water for raising said float means by way of flotation to the predetermined level.
